UNITED STATES PATENT OFFICE

PETER V. JALI AND FRED C. WORRALL, OF PORTLAND, OREGON

ALFALFA MILL

Application filed February 26, 1930. Serial No. 431,495.

This invention relates broadly to pulverizing mechanism and more particularly to an alfalfa mill.

The primary object of this invention is to provide a mill of the character above mentioned, including an especially shaped casing or housing for receiving the alfalfa or material to be pulverized together with a rotor arranged within the housing having a plurality of hammers associated therewith, the hammers and the side walls of the casing being so arranged relatively to one another as to insure a thorough pulverizing of the material to be so treated.

15 A still further object of the invention is to provide a pulverizing device of this character, which comprises but comparatively few parts, can be readily and easily set up, will be thoroughly reliable, practical, and efficient in operation, and otherwise well adapted for the purpose designed.

20 Other objects and advantages of the invention will become apparent during a study of the following description, taken in connection with the accompanying drawings, wherein:

25 Figure 1 is a front elevational view of a mill embodying the features of the present invention.

30 Figure 2 is a vertical longitudinal sectional view taken therethrough, substantially on line 2—2 of Figure 1.

35 Figure 3 is a vertical transverse sectional view taken through the device for more clearly showing the structure of the side walls and their relation relative to the pulverizing hammers.

40 With reference more in detail to the drawings, it will be seen that our improved mill comprises a base or platform 5 upon which is mounted a grain receiving housing designated generally by the reference character 5. As suggested in Figure 2, the base 5 is of oblong or elongated rectangular configuration and inwardly from the longitudinal side edges thereof rises the front and rear walls 6 and 7 respectively of the housing, said walls rising in spaced parallelism.

45 The said front and rear walls are connected through the medium of the angular

connecting walls 8—8. The connecting walls are identical in construction, and as shown to advantage in Figure 3, each of said walls comprise a vertical intermediate wall section 9, a downwardly and inwardly directed bottom forming wall section 10, the bottom forming wall sections 10 meeting at their lower ends to form a substantially V-shaped bottom designated generally by the reference character 11 for the housing.

50 The said connecting walls 8 further embody the wall section 12 extending upwardly and inwardly from the upper edge of the intermediate vertical wall section 9, which wall section 12 in turn merges into an upwardly and inwardly directed wall section 13, the wall section 13 providing a restricted outlet opening 14 at the top of said housing.

55 Each of the sections of the walls 8 at their ends are provided with outwardly directed attaching flanges 15 secured to the front and rear walls 5 and 6 by suitable fastening means such as the nut and bolt connections 16. Rising from the restricted outlet opening 14 in the top of the housing is an outlet pipe or 60 tube 17.

65 The front wall 5 is provided with an intake or filling opening 18, as shown to advantage in Figure 2. If desired a material feed chute or tube 19 at its lower end may be disposed in registry with the intake opening 18 for conducting the material, such as alfalfa or the like, into the housing to be pulverized in a manner hereinafter to be more fully set forth.

70 Said front wall 6 adjacent the bottom thereof is provided with an outlet opening 19 to permit access to be had to the interior of the housing at the bottom thereof.

75 Mounted within the housing, is a rotor 20 designated by the reference character 20, which rotor is of circular configuration, and is provided with, and projecting from opposite ends thereof stub shafts 21, which shafts 21 extend through the front and rear walls 95 of the housing, said stub shafts being journaled in suitable bearings 22 exteriorly of the housing, the bearings being supported on suitable brackets 23—23, suitably secured to the front and rear walls 6 and 7.

The rotor 20 has a plurality of arms 24 projecting radially therefrom and pivotally secured to the ends of these arms are pulverizing hammers, designated generally by the 5 reference character 25.

Since each of these hammers are identical in construction, it is thought that a detailed description of one will suffice. Each of the 10 said hammers 25 comprises a pair of relatively short angle irons 26 with their corresponding ends disposed one to each side of the arm 24 and pivotally secured thereto through the medium of a bolt 27 extending through said ends and the end of the arm, 15 and a nut 28 is threaded on the end of the bolt for securing the ends of the angle irons to the outer ends of the arms, as clearly suggested in Figure 2.

A cross bar or connecting plate 29 is bolted 20 as at 30 at its opposite ends to the flanges 31 of the angle bars 26 completing the structure of the hammer. It is to be noted that the longitudinal edge of the connecting bar 29 is flush with the ends of the angle bars 26, 25 the web of the connecting bar or plate 29 being substantially equal to more than half the length of said angle bars 26.

The spindle 21 of the rotor extending 30 through the rear wall 7 of the housing has splined thereto a suitable drive wheel 32 whereby rotative movement is imparted to the rotor from any suitable source of power.

An arcuate shaped screen 33 extends between the connecting walls 8 and has its ends 35 secured to the upper converging edges of the wall sections 12 as at 34.

It is to be noted that the hammers 25 pivotally carried to the arms 24 of the rotor, have 40 their outer ends terminating close to the wall sections 9, 10, and 12, and especially is this fact to be noted with respect to the inclined bottom forming walls 10 since it will be appreciated that during the rotation of the rotor in a clockwise direction, the downward 45 swinging movement of the hammers 25 upon their pivots will enable the hammers to strike with the maximum force, with a terrific blow on the material to be pulverized resting on the walls 10 and this being so since it is obvious that this swinging or pivotal connection of the hammers lends greater impetus to the hammers during the rotation of the rotor than if the hammers were fixedly secured to the outer ends of the arms 24 of the rotor.

55 Another feature to be noted, is in the particular shape of the connecting walls 8 since such shape of the walls in conjunction with the rotation of the rotor and the hammers 25 will result in suitable friction being 60 formed at the filling or intake opening 18 to automatically assist in drawing the material to be pulverized into the housing and downward to the left of the housing.

Further, the peculiar shape afforded the 65 housing by the walls 8 and the rotation of

the rotor 20 will cause a suction to the right within the housing and draw the pulverized alfalfa or material up through the screen 33 to exit through the outlet opening 14.

Furthermore, through the medium of the 70 inclined sections 10 forming the V-shaped bottom 11 of the housing, will permit hard objects, such as metal and other material unsuitable to be pulverized to drop through the bottom of the housing and there be removed through the opening 19 in the bottom of the front wall 6.

It will also be appreciated that in having the hammers pivotally secured to the ends 80 of the arms 24, the hammers coming in contact with any article which is too hard to pulverize will of course be swung about their pivots to pass over such articles and in this way eliminate any danger of the hammers being torn away from their connection to the 85 rotor arms 24 as is apparent.

It is thought that from the foregoing description, taken in connection with the accompanying drawings, a clear understanding 90 of the operation, construction, utility and advantages of an invention of this character will be had without a more detailed description.

Even though we have herein shown and described the preferred embodiment of our 95 invention, it is to be understood that the same is susceptible to changes fully comprehended by the spirit of the invention as herein described, and the scope of the appended claims.

Having thus described our invention, what 100 we claim as new is:

1. In a pulverizer of the class described, a casing including front and rear walls, side walls inclining downwardly and inwardly at their lower ends to provide a substantially V-shaped bottom, and inclining upwardly and inwardly at their upper portions, the upper edges of the side walls terminating in spaced relation to provide a restricted outlet, said front wall being provided adjacent its upper portion with an inlet opening, a rotor in said casing, radial arms on said rotor, and pulverizing hammers pivotally secured to the outer ends of said arms.

2. In a pulverizer of the class described, a casing comprising parallel front and rear walls, side walls connecting said front and rear walls, each of said side walls comprising relatively vertical sections, downwardly and inwardly inclined bottom forming sections, upwardly and inwardly inclined sections inclining upwardly from said vertical sections, said last mentioned section terminating in an upwardly and inwardly directed section, said last mentioned sections of said side walls terminating in spaced parallelism to provide a restricted opening in the top of said casing, a rotor in the casing, and a plurality of radially disposed pulverizing hammers mounted on said rotor.

3. In a pulverizer of the class described, a casing comprising parallel front and rear walls, side walls connecting said front and rear walls, each of said side walls comprising relatively vertical sections, downwardly and inwardly inclined bottom forming sections, upwardly and inwardly inclined sections inclining upwardly from said vertical sections, said last mentioned section terminating in an upwardly and inwardly directed section, said last mentioned sections of said side walls terminating in spaced parallelism to provide a restricted opening in the top of said casing, a rotor in the casing, and a plurality of radially disposed pulverizing hammers mounted on said rotor, the front wall of said housing having an opening in a portion thereof whereby material to be pulverized may be drawn into the housing to provide a suction created in the housing during the rotation of said rotor.

4. In a pulverizer of the class described, a casing comprising parallel front and rear walls, side walls connecting said front and rear walls, each of said side walls comprising relatively vertical sections, downwardly and inwardly inclined bottom forming sections, upwardly and inwardly inclined sections inclining upwardly from said vertical sections, said last mentioned section terminating in an upwardly and inwardly directed section, said last mentioned sections of said side walls terminating in spaced parallelism to provide a restricted opening in the top of said casing, a rotor in the casing, and a plurality of radially disposed pulverizing hammers mounted on said rotor, the front wall of said housing having an opening in a portion thereof whereby material to be pulverized may be drawn into the housing to provide a suction created in the housing during the rotation of said rotor, said front wall having an opening in the bottom thereof whereby access may be had to the bottom of said housing, an arcuate shaped screen disposed across the discharge opening in the top of the housing transversely of the housing.

In testimony whereof we affix our signatures.

59 PETER V. JALI.
FRED C. WORRALL.
